UNITED STATES PATENT OFFICE.

SAMUEL H. DUNLAP, OF ENNIS, TEXAS.

GIN-COMPRESS.

1,305,783.

Specification of Letters Patent. Patented June 3, 1919.

Application filed April 3, 1917, Serial No. 159,537. Renewed October 22, 1918. Serial No. 259,299.

To all whom it may concern:

Be it known that I, SAMUEL H. DUNLAP, a citizen of the United States, residing at Ennis, in the county of Ellis and State of Texas, have invented new and useful Improvements in Gin-Compresses, of which the following is a specification.

This invention relates to gin compresses and the object is to provide a construction which will be more effective than that heretofore employed in accomplishing the purpose to be attained by a device of the character specified.

The improved construction may include a compress in which the following is operated by a plurality of screws driven in suitable manner, as for instance a horizontal shaft with gearing transmitting power to the screws, said gearing being controlled by means of shifting mechanism operated manually, or operated automatically by the movement of the follower.

In the accompanying drawing forming part of this specification,

Figure 1 is a view partly in vertical section and partly in elevation.

Fig. 2 is a view taken on line 2—2 of Fig. 1 and showing certain of the operative mechanism in top plan.

Fig. 3 is a view partly in elevation showing further details of the mechanism for controlling the speed of the shaft driving the operating screws.

Fig. 4 is a detail of construction described below.

Figs. 5 to 8 show modified forms of certain features and are chiefly in elevation, Fig. 7, however being on line 7—7 of Fig. 5.

Describing the construction in detail, I have shown a bed plate 10 supported upon iron girders or I-beams 12 with heavy vertical columns 14 carrying an upper cross head 15, the latter being retained in position by means of set collars 16 and nuts 18 carried on the upper ends of the columns.

The bed plate 10 is recessed to form a chamber for receiving certain of the operative devices, and a cap plate 20 is secured to the outer portions of the bed plate by means of bolts 21. Set collars 22 are secured to

the column 14 immediately above the cap plate 20. Heavy screws 24 are provided for operating the follower block 25, and this block as well as cross head 15 is slotted in the manner shown for the purpose of receiving the bale ties.

Each screw 24 engages an internally threaded worm wheel 26 located between the bed plate 10 and the cap plate mentioned, and the worm wheels are provided with oppositely extending collar portions 28 and 29 which are received by recesses within the cap plate and bed plate. Thrust bearings are shown at 30.

The worm wheels are engaged by worms 31 on horizontal shaft 32 affording means for driving the screws. The shaft 32 carries a gear 35 having an inner notched portion 36 and rigidly connected with the wheel proper and with the notched portion is the pinion 37 which meshes with a pinion 38 driven by means of pulley 39. The pinion 38 is eccentrically mounted with reference to the wheel 35 and by shifting the position of said pinion by means of handle 40 the pinion is caused to engage pinion 37 or the toothed portion 36 as may be desired. The handle or lever may be thrown to neutral position for stopping the press. A portion of the framework of the machine adjacent to the structure above described and supporting the latter is designated 45.

The pinion 38 may be shifted to neutral position for the purpose of stopping the press by means of arm 49 and a rod 47 which extends upwardly adjacent to one of the columns 14 and is provided with stops 48 to be engaged by the follower upon reaching predetermined points in the upward movement and in the downward movement thereof. This safety device may be thrown out of engagement when desired.

The controlling lever 40 is pivoted at 40' and controls pinion 38 on shaft 38', the pinion being eccentric with reference to the toothed members with which it meshes. When engaging the outer toothed member the speed is very much reduced and the power greatly increased. When engaging pinion 37 the opposite effect is attained. A

speed of three hundred revolutions per minute is more than sufficient to compress cotton to the required density, the gearing and operative parts being proportioned to accomplish that result at less than the speed named.

The threaded screws 24 operate within a casing 50 and this casing and the chamber between the bed plate 10 and cap plate 20 are filled with oil for the purpose of providing easy running and for effecting a dust-proof construction.

In the construction shown in Fig. 5 the casing 60 extends upwardly to the bed plate 10, forming a protecting element for each of the screws similar to that formed by casing 50 above described. The chamber formed within the bed plate for lubricating material is therefore in continuous communication with the chambers within casings 60 so that the operative mechanism will be inclosed in an oil bath.

In Fig. 5 a modified form of mechanism for controlling shaft 32 is illustrated, and this form further appears in Fig. 7. The driving belt 62 transmits motion to pulley 63 provided with internally toothed portion 64 adapted to mesh with a pinion 65' carried on main shaft 32. The position of pulley 63 is controlled by means of an operating lever 66 pivoted at 67 on frame 68 and provided with a curved slot 69. Pulley 63 is rigid with a short shaft 67 having a collar 68 thereon passing through said slot 69. The operation of lever 66 will therefore control the position of pulley 63 by imparting shifting movement to the short shaft on which it is mounted, and the operating lever is further controlled automatically by rod 47' extending to a point which will permit of its control by the plunger.

In the form shown in Fig. 8 the position of pulley 63 (provided with the internal toothed flange member 64) is controlled by means of a rack bar 70 having connection with the end of short shaft 67. The pinion 65 carried by this shaft may therefore be brought into proper relation with pinion 65' for producing the reversing operation, or for shifting to neutral position, the reciprocation of rack bar 70 being accomplished by means of lever 72 having a segmental rack portion 73, said lever being pivoted at 74 and the segmental portion having connected therewith a rod 47' extending upwardly into position where it may be engaged by the plunger.

In Fig. 6 I have illustrated modified forms of the follower block and head block, these members being designated 75 and 76 and each being provided with a concave portion 78 or 79, between which the cotton is compressed. When compressing a square or rectangular bale, and securing a given degree of density, the surfaces of the bale will ex-

pand after the latter has been withdrawn from the press, and after the ties have been applied thereto, the bale then having convex surfaces and the density being materially reduced in given portions thereof. This objectionable feature is avoided by employing the construction specified whereby a bale of a given density throughout may be produced, and one which will retain its uniform density and its original form after the ties have been applied and a bale removed from the press. By this means a round or partially round bale is produced.

I claim:—

1. In a device of the class described, a framework, a follower operating therein, a screw for operating the follower, a shaft, and means carried thereby for operating the screw, and a speed changing and reversing device for controlling the shaft, said device last-named including a plurality of pinions adapted to mesh with each other at times, a toothed member adapted to mesh with one of the pinions at times, and means for changing the position of one of the pinions with reference to the other, said means last named including a lever pivotally mounted at one end thereof, a laterally extending device carried by the lever and including a cam slot positioned between the fulcrum of the lever and the handle thereof, said slot controlling the position of one of the pinions, and adjustable means operated from the follower, and having connection with said lever near the fulcrum thereof.

2. In a device of the class described, a framework, a follower operating therein, a screw for operating the follower, a shaft, and means carried thereby for operating the screw, and a speed changing and reversing device for controlling the shaft, said device last-named including a plurality of pinions adapted to mesh with each other at times, a toothed member adapted to mesh with one of the pinions at times, and means for changing the position of one of the pinions with reference to the other, said means last mentioned including a pivotally mounted lever provided with a cam slot controlling the position of one of the pinions with reference to the other of said pinions, and means for automatically controlling the lever by the follower.

3. In a device of the character described, a framework including a bed plate having a recess therein, a follower, operative mechanism connected with the follower and positioned within the recess, means for closing the recess and providing an oil chamber, and an additional oil chamber located beneath the bed plate and inclosing a portion of the operative mechanism.

4. In a device of the class described, a framework, a follower operating therein, a bed plate provided with apertures and with

annular recesses surrounding the apertures, a cap plate recessed and apertured to correspond with the bed plate, inclosed chambers being provided between the cap plate and bed plate, worm wheels and thrust bearings therefor mounted in the recesses, said wheels having threaded bores, screws engaging the threaded bores and operating

the follower, a worm shaft engaging the worm wheels, and means for driving the shaft at different speeds and imparting movement in corresponding degree to the follower.

In testimony whereof I affix my signature.

SAMUEL H. DUNLAP.
